(57) **CLAIM**

I claim the ornamental design for an enhancement panel retaining assembly for a window, as shown and described.

DESCRIPTION

FIG. 1 is a perspective view of an enhancement panel retaining assembly for a window.

FIG. 2 is a perspective view of the detached top member of an enhancement panel retaining assembly for a window.

FIG. 3 is a perspective view of the detached bottom member of an enhancement panel retaining assembly for a window.

FIG. 4 is a top plan view of the detached top member of an enhancement panel retaining assembly for a window shown in FIG. 2; and,

FIG. 5 is a top plan view of the detached bottom member of an enhancement panel retaining assembly for a window shown in FIG. 3.
